UNITED STATES PATENT OFFICE.

WILLIAM E. FOWLER, SR., OF CHICAGO, ILLINOIS, ASSIGNOR TO THE FOWLER CAR COMPANY, OF CHICAGO, ILLINOIS, A CORPORATION OF ILLINOIS.

CAR SIDE.

1,093,839.

Specification of Letters Patent. Patented Apr. 21, 1914.

Application filed September 29, 1913. Serial No. 792,265.

To all whom it may concern:

Be it known that I, WILLIAM E. FOWLER, Sr., a citizen of the United States, and resident of Chicago, in the county of Cook and 5 State of Illinois, have invented certain new and useful Improvements in Car Sides, of which the following is a specification.

My invention relates to railway cars and has particular reference to a novel metallic 10 frame single sheath car, similar to that shown in my former Patent No. 962,425.

In the construction of cars known as the Fowler type, that is, metallic frame box cars having a single interior sheathing, the 15 sheathing planks running longitudinally of the car, it is customary to attach the planks to the frame by means of bolts, the bolts projecting through slots punched in the frame. Even if only every alternate plank 20 is secured to the frame this requires a very large number of operations in punching the metallic members, which operations not only increase the labor cost but materially weaken the frame members. I have therefore 25 conceived the idea of providing for means of securing the sheathing members in proper position and maintaining the same without punching any of the frame members.

In practice it has been found not only desirable 30 but essential that permanent means be associated with the car whereby the side planks may be kept in close relation to take up shrinkage and warping. One of the most efficient means is the inside strap extending from the top of the side planks 35 down to the floor, a tightening nut finding a bearing on the flange of the side sill. I have conceived the idea of forming this tightening strap of an angular shape where- 40 by to provide suitable lateral stiffness using this strap as a side plank retaining means, this strap or angular member acting in place of the usual bolts which passed through the metallic frame members. Preferably this 45 angular member is gained into the boards in order to provide a flush interior surface.

The invention will be more readily understood by reference to the accompanying drawings, wherein,

50 Figure 1 is a side elevation of a portion of a box car constructed in accordance with my invention; Fig. 2 is a fragmentary vertical section of the construction shown in Fig. 1; Fig. 3 is an enlarged vertical section similar to that shown in Fig. 2; Fig. 4 is an

enlarged view of an elevation partly in section of the top securing means for the tightening strap; Fig. 5 is a similar view showing the intermediate tightening means; Fig. 6 is a section on the line 6—6 of Fig. 5, 60 and Fig. 7 is an enlarged fragmentary detail showing the corner construction of the tightening strap.

Referring more particularly to the drawings it will be seen that a car embodying 65 my invention may consist of a side sill 10, top plate 11, vertical posts 12, diagonal posts 13, and corner post 14. The car is provided with a single interior sheathing consisting of planks 15 extending longitudinally of the 70 car. Preferably located at each vertical post and gained into the planks 15, as shown at 16, in Fig. 6, I provide an angular preferably channel-shaped post or strap 17, extending from top to bottom of the car. At 75 the top the flanges 17^a of the channel are cut off and the web is bent over to form a hook which hook engages with the top plank 15. At the bottom I preferably rivet a round rod 18, having a threaded lower end 19, 80 which rod extends through openings in the side sill 10, and is engaged by a nut 20, whereby pressure may be exerted to tighten the sides by a downward pull on the strap or post. In order to maintain the sheathing 85 in operative relation to the frame, I provide a bolt 21, which passes through the upper plank 15, and has its head seated within the space between the legs of the channels 17. As a means for providing a bearing on the 90 frame I provide an upper loop composed of straps 22, the ends of which are riveted to the frame at 23, and between which the bolt 21 projects. There is thus provided an extended slideway which permits vertical 95 movement of the planks as required in tightening. It may be found desirable to provide also an intermediate bolt 24, the head of which is likewise seated in the angular member 17, and the shank projecting through a loop formed by the straps 25, riveted to the frame member at 26. Owing to the stiffness of the angular post or strap, however, such intermediate fastening may not be found necessary in all cases. The means for holding the strap at the bottom, of course, will be understood is the rod 18, which passes through neat holes in the channel flanges 10. A similar construction may be followed at 105 the ends or simple straps 27, may be bent 110

around the corner, short bolts passing through the angular member sheathing and strap, as shown in Fig. 7. This obviates the necessity for punching the corner post 14. 5 It will be understood that the corner angle 14, is not apertured the fastening bolt merely abutting the edge of the angle. 10 In the construction shown a car is provided which retains all the requisites of a box car but which may be very cheaply constructed in view of the lack of necessity for punching the frame members and boring of the side planks together with the ease in assembling and facility in making repairs. 15 Obviously, many modifications may be made and such modifications as are within the scope of my claims I consider within the spirit of my invention.

I claim:

- 20 1. In a railway car, the combination of a metallic frame and a single, interior, longitudinally extending sheathing, a metallic strap located interiorly of the car with its edges flush with the surface of said sheathing, and a bolt securing said strap and said sheathing to the frame, said bolt extending to one side of a frame member, substantially as described. 25 2. In a railway car, the combination of a metallic frame posts, a single, interior, longitudinally extending sheathing, an angular tightening strap and retaining member located on the inside of the car, said member having engagement with said sheathing near

the top thereof and extending through the 35 floor of the car, means for exerting downward pressure on said strap to tighten said sheathing, and means for securing said sheathing to the frame, said securing means being connected to said tightening strap and 40 being located adjacent to but not passing through a frame post, substantially as described.

3. In a railway car, the combination of a metallic frame, a single interior, longitudinally extending sheathing, an interior, angular post extending from top to bottom of the car, a loop secured to a frame post, and securing means passing through said interior post and coöperating with said loop 50 whereby to retain said sheathing in position, substantially as described.

4. In a railway car, the combination of a metallic frame, a single interior longitudinally extending sheathing, an interior post, 55 a strap coöperating with the frame exteriorly of said frame and sheathing, and a bolt passing through said post and said strap and extending to one side of a frame member, substantially as described. 60

Signed at Chicago, county of Cook and State of Illinois, this 26th day of September, 1913.

WILLIAM E. FOWLER, Sr.
